UNITED STATES PATENT OFFICE.

MARIA STINGHE WAGNER, OF NEW YORK, N. Y.

TROUSERS.

Application filed March 2, 1927. Serial No. 172,021.

This invention relates to improvements in wearing apparel, and has particular reference to a pair of trousers.

An object of the invention is to provide an improved construction of trousers which will be simple, practical and have a neat appearance when worn.

Another object is to provide the trousers with a belt which is secured to the waist portion of the trousers at the hip sections thereof with the front portion of the belt, when closed, simulating in appearance the lower part of a waistcoat or vest, the rear portion of said belt extending interiorly of a back portion of the trousers which is also secured at the hip sections both to the front portion of the trousers and to said belt.

The above and other objects will appear more clearly from the following detail description, when taken in connection with the accompanying drawing, which illustrates a preferred embodiment of the inventive idea.

In the drawing—

Although the invention is shown in connection with knickerbockers, it will, of course, be understood that the inventive idea may be applied to other types of trousers without departing from the spirit or scope of the invention.

The trousers, as shown, comprise the leg sections 4 and the front portion 5 which is, generally speaking, of the same construction as the usual type of trousers except that said portion is made longer than customary so that the upper end extends a greater distance above the waist than is the case in ordinary trousers. The waist part of the trousers further consists of a back portion 6 which extends approximately half way about the waist and is provided upon its forward vertical edges with a series of button-holes 7 for attaching said back portion over each hip to a plurality of buttons 8, certain of which are secured to the trousers proper while others are fastened to the adjacent portion of the belt 9, as shown in Figure 3. The buttons 8 over each hip are arranged to form two rows with the two 55 lowermost buttons common to both rows while the remaining buttons in each row are disposed at an angle to those in the other row. This arrangement of the buttons permits of attaining a certain amount of adjustability 60 in attaching the back portion in position so that it may be made to fit comfortably about the waist and hips.

The front portion of the belt 9 extending from the hips around the front of the trousers comprises two sections 10, the width of each gradually increasing from the hip end so that when the free ends of said sections, which are quite wide, are secured together by the buttons 11 and holes 12 the front portion of the belt will have the appearance of 65 the lower part of a vest and this appearance will be enhanced by the fact that the waist portion of the trousers is made considerably 70 higher than is ordinarily done. The back portion of the belt 9, which extends from over the hips around the back and to which the uppermost buttons 8 are secured, is divided into sections 13 and 14, the former 75 consisting of fabric of which the trousers 80 are made while the latter comprise a series of elastic strips which impart elasticity to the belt so that it will fit snugly about the waist and thus maintain the trousers in proper position about the hips. When the 85 trousers are in position and the back portion 6 is closed, the upper part of said portion extends exteriorly of the back of the belt 9 so that said back is entirely covered, thus further enhancing the neat appearance of 90 the garment.

What is claimed is:

1. A pair of trousers comprising a waist section including front and back portions, a waist encircling belt secured to the waist 95 section over the hips and having the front portion thereof simulating a part of a waistcoat, and a plurality of fasteners secured to said front portion and to said belt over the hips, said fasteners being arranged in upwardly diverging rows to either of which may be secured said back portion.

2. A pair of trousers comprising a waist section including front and back portions,

a waist encircling belt secured to the waist section over the hips and having the front portion thereof simulating a part of a waist-coat, and a plurality of fasteners secured to said front portion and to said belt over the hips, said fasteners being arranged in upwardly diverging rows to either of which may be secured said back portion, and said back portion of the waist section covering the back portion of said belt when the former is secured to said fasteners. ¹⁰

In testimony whereof I have affixed my signature.
